UNITED STATES PATENT OFFICE

HARRY S. DEMAREE, OF CHICAGO, ILLINOIS, ASSIGNOR TO THE HOOVER COMPANY, OF
NORTH CANTON, OHIO, A CORPORATION OF OHIO

SUCTION CLEANER

Application filed February 3, 1930. Serial No. 425,371.

The present invention relates to the art of suction cleaners, and more particularly to positive agitating means used in suction cleaners.

5 The use of a rotating agitating member in the nozzle of a suction cleaner which is adapted to clean surface coverings is well known. The agitator may be driven either by the driving motor which drives the fan to create the suction for the cleaner or it may be driven by the supporting wheels at the nozzle end of the machine. In the operation of a suction cleaner embodying a positive agitator the surface covering undergoing cleaning is lifted by suction against the lips of the nozzle and the rotating agitator contacts the uplifted covering therebetween functioning to disturb and dislodge the embedded foreign matter within the covering so that 10 the cleaning air rushing through the nozzle may remove it to the dirt separator which is connected to the cleaner. Rotating brushes have been used in the nozzle as a means of agitation and while such agitators serve to remove the foreign matter lodged near the top of the surface covering, the deeply embedded matter remains embedded, resulting in inefficient cleaning. To effect 15 the removal of the deeply embedded matter a distinct blow must be imparted to the surface covering and to effect this result agitators comprising rigid elements are used, in combination in many cases, with the brush construction.

20 The present invention is directed to that form of rotary agitator which embodies solely positive or rigid agitating means and in which no brush structure is provided.

An object of the present invention is to 25 provide a new and novel agitator for suction cleaners. A further object is the provision of a simplified rotor construction for suction cleaners. A still further object is the provision, in a suction cleaner, of a simplified agitator construction which is capable of being made in large quantities in an economical manner.

30 Referring now to the drawing:

Figure 1 discloses a view in perspective of

a suction cleaner agitator, constructed in accordance with the present invention.

Figure 2 discloses a cross-sectional view of a modified form of the present invention.

Figure 3 is a cross section upon the line 55 3-3 of Figure 1.

Figures 4, 5, 6 and 7 are sections of modified shapes of bodies which may be used in the present invention.

Referring now to Figure 1 in particular, 60 an agitator constructed in accordance with the present invention is indicated generally by the reference character 1. The agitator comprises a hollow metallic body 2 having a cross section as shown in Figure 3. Body 2 is 65 formed of drawn or rolled metal of sufficient thickness to provide the necessary strength and rigidity to prevent distortion when in use. Spaced projecting portions or protrusions, indicated by the reference character 3, 70 3, are formed in body 2 and comprise the points in the body periphery at a maximum distance from the geometric center. These projections function, as will be hereinafter described, as the surface contacting portions 75 or beaters of the agitator. Body 2 has been provided with an angular twist between its longitudinal ends so that the projections 3, 3 describe helices therebetween.

Positioned at the opposite ends of body 2 80 and retained therein in any suitable manner, as by welding, are end plates, as indicated by the reference character 4. At one of the ends of the agitator a cylindrical member, indicated by the reference character 5, which is 85 provided with a circumferential groove 6, is carried by the end plate 4 and forms a pulley by which the agitator may be rotated by means of a belt. The pulley 5 may be formed as an integral part of the plate 4 and both 90 the plate and the pulley attached to one end of the agitator and secured in any suitable manner, as aforescribed. The maximum radius of pulley 5 should be substantially less than the radial distance of projection 3 from 95 the axial center of the agitator body so that in the operation of the agitator the surface covering will contact the beating projections and not the pulley.

In order that the agitator may be rotat- 100

ably supported within suitable bearings in the nozzle of the suction cleaner stub-shafts, indicated by the reference characters 7, 7, are provided at the opposite ends of the agitator 5 body which are seated in the end plates 4 and extend in the longitudinal axis of the agitator. The particular manner in which the agitator is mounted within the nozzle of the suction cleaner forms no part of the present 10 invention and may be accomplished in many ways.

In operation, the agitator constructed in accordance with the present invention, is revolved about its longitudinal axis, being supported upon the stub-shafts 7, 7. The driving power to rotate the agitator is provided by means of a suitable belt connection between the driving motor of the suction cleaner and the pulley 5. Upon being rotated the salient 15 portions 3, 3 of the agitator contact the surface covering and, upon the agitator being revolved at high speed, deliver impacts at high frequency to the covering. The embedded foreign matter is dislodged by the successive impacts and its removal is accomplished by the cleaning air passing through the nozzle in which the agitator is located.

Referring now to Figure 2, in particular, the cross-sectional view through a modified 30 body form susceptible of embodiment in the present invention is disclosed. An agitator, constructed in accordance with Figure 2, differs only from the one constructed in accordance with Figure 1 in the structural 35 shape of the body member. The construction retains the characteristic of having certain portions 3, 3 which extend a maximum distance from the geometrical center and which are adapted to function as beating elements.

40 Figures 4, 5, 6 and 7 disclose further structural shapes into which the body 2 may be formed by rolling or drawing. Depending upon the type of surface covering upon which the cleaner embodying the agitator constructed in accordance with the present invention is to be used a certain frequency of impact is found most effective. With structural shapes embodying a relatively 45 large number of projections 3, 3 the frequency 50 of the impacts imparted to the covering will be greater at a definite speed of agitator rotation. In surface coverings in which relatively low frequency of impact is desirable those structural shapes embodying a minimum 55 number of beating projections 3, 3 would be employed.

I claim:—

1. An agitator for suction cleaners comprising a twisted hollow shell characterized 60 by a plurality of helically extending protrusions, plates secured at the ends of said shell, means adapted to receive a rotating torque for said shell and means to rotatably support said shell and end plates.
- 65 2. An agitator for suction cleaners com-

prising a body, end plates secured to said body and means to receive a rotating force, characterized by the fact that said body comprises a twisted shell having a polygonal cross-section.

3. An agitator for a suction cleaner comprising an elongated body having a plurality of sides, means to support said body, and means to receive a rotating force, characterized by the fact that the junctions of certain 75 sides of said body define helically extending protruding portions at a maximum radial distance from the longitudinal axis of the body.

4. A rotary agitator for a suction cleaner 80 including a body formed of an elongated twisted shell, characterized by the fact that said body is a multilateral geometrical figure in a plane at right angles to the longitudinal axis with no outwardly facing acute 85 angles and with spaced integral portions at equal maximum radial distances from said longitudinal axis, and means to rotatably support said body.

5. A rotary agitator for a suction cleaner 90 including a body formed of an elongated twisted shell, characterized by the fact that said body is a multilateral geometrical figure in a cross-sectional plane at right angles to the longitudinal axis with no outwardly facing acute 95 angles and with spaced integral portions at maximum radial distances from the longitudinal axis and is bilaterally symmetrical about any plane through the longitudinal axis and means to rotatably support 100 said body.

Signed at Chicago, in the county of Cook and State of Illinois, this 29th day of January, A. D. 1930.
